UNITED STATES PATENT OFFICE.

OSCAR E. BRANDT, OF CHICAGO, ILLINOIS, ASSIGNOR TO THE W. W. KIMBALL COMPANY, OF SAME PLACE.

DESIGN FOR THE TOP OF AN ORGAN-CASE.

SPECIFICATION forming part of Design No. 21,882, dated October 4, 1892.

Application filed April 11, 1892. Serial No. 428,717. Term of patent 3½ years.

To all whom it may concern:

Be it known that I, OSCAR E. BRANDT, a citizen of the United States, residing at Chicago, in the county of Cook and State of Illinois, have invented a new and original Design for the Top of an Organ-Case, of which the following is a specification.

This invention relates to a new design for the superstructure or ornamental top with which many cabinet-organs are now provided.

The design is shown in perspective in the accompanying drawing, and its leading feature consists in a recessed top having a long arch extending from end to end of the case placed in the front of the recess.

In the drawing, A represents the corner-posts of the top, and B B the ends of the top. C is the long arch referred to, extending from one front corner-post to the other and placed in front of the recess D, formed in the top. 20

I claim—

The design for the top of an organ-case, substantially as herein set forth.

OSCAR E. BRANDT.
